(57) **CLAIM**

The ornamental design for a vanity as shown and described.

DESCRIPTION

FIG. 1 is a perspective view of the vanity;

FIG. 2 is a front elevational view of the vanity;

FIG. 3 is a rear elevational view of the vanity;

FIG. 4 is a left side elevational view of the vanity;

FIG. 5 is a right side elevational view of the vanity;

FIG. 6 is a top plan view of the vanity; and

FIG. 7 is a bottom plan view of the vanity.

FIG. 8 is a perspective view of a second embodiment of the vanity of my new design;

FIG. 9 is a front elevational view of the vanity;

FIG. 10 is a rear elevational view of the vanity;

FIG. 11 is a left side elevational view of the vanity;

FIG. 12 is a right side elevational view of the vanity;

FIG. 13 is a top plan view of the vanity; and,

FIG. 14 is a bottom plan view of the vanity.

The broken line portions of the drawings are included to show portions of the article that form no part of the claimed design and represent environmental structure only.
